UNITED STATES PATENT OFFICE.

WILLIAM S. BEAZELL, OF LAKEWOOD, OHIO.

CARD HOLDER.

Application filed July 7, 1926. Serial No. 121,031.

The present invention relates to a card or sign holding bracket, and has for its object to provide a device of this character which embodies novel features of construction, whereby the sign or card can be easily and quickly placed in position or removed therefrom, and when in place will be held in a conspicuous position so that it can be readily seen at a distance.

10 The invention is more particularly designed for use in supporting cards of that type which are used in houses to inform the drivers of certain trucks that the occupants of the house desire them to stop and deliver 15 their wares. Cards of this general type are frequently distributed among their customers by ice companies, bakeries and the like, with instructions to place the card in a conspicuous position at the front of the house 20 when it is desired to have the driver of one of their wagons stop. In some instances the card is printed or designed so that it can be turned into different positions to indicate the exact commodity or exact amount of the 25 particular commodity desired, thereby enabling the driver to deliver just what is wanted on his first call without having to make a first trip to find out what is wanted and a second trip to deliver the goods.

30 The present holder or bracket admits of such a card being easily and quickly placed in position or removed therefrom and securely holds the card in place so that it can be easily seen by a person or driver passing 35 the house. The card may be clamped so that it can be held in any desired angular position and cannot be blown away by the wind.

While one particular embodiment of the 40 invention is shown on the drawing and described in the specification for illustrative purposes, it will be understood that many modifications and changes can be made in the details of construction without departing from the spirit of the invention.

45 For a full understanding of the invention as claimed reference is to be had to the following description and accompanying drawings in which,

50 Figure 1 is a front elevation of a card holder which is constructed in accordance with the invention, the card being shown as clamped in position thereby and portions of the card being broken away.

55 Figure 2 is a side elevation of the device with the card shown in section, the retaining bar being shown by full lines in the position

assumed when holding a card in position, and by dotted lines in the position assumed when it is swung outwardly to admit of a card or the like being placed in position in 60 the holder or removed therefrom.

Figure 3 is a front elevation of a slightly modified form of the invention in which the holder is mounted on the end of an arm.

Figure 4 is a top plan view of the construction shown by Figure 3.

Corresponding and like parts are referred to in the following description and indicated on all of the views of the drawing by like reference characters.

70 Referring to the drawings, which illustrate two of many possible embodiments of the invention, the numeral 1 designates a flat base against which a card or like member 2 is adapted to be held by means of a 75 retaining bar 3. The base 1 may be of a suitable size and shape, as shown by Figure 2, and is adapted to be secured to a suitable support 4 by means of a screw 5 or other fastening member.

Projecting from the front of the flat base 1 is a short stem 6, and the card or sign 2 is intended to be formed with a suitable opening 7 to receive the stem when the card is in position. The short stem 6 is provided with a pin 8 which 80 is loosely received within a slot 9 in the retaining bar. In the preferred form of the invention, as shown by the drawings, the end of the stem 6 is bifurcated to receive the retaining bar 3 and the pin 8 extends 85 transversely across the bifurcation. The slot 9 in the retaining bar extends from an intermediate point therein to a point near one of the ends of the bar, and when the bar is moved longitudinally to bring the pin 90 95

8 into the outer end of the slot 9, the retaining bar can be swung upon the pin as a center into a position at right angles to the base 1 and in alignment with the stem 6 or into a position parallel to the base 1 and at right angles to the stem 6. The ends of the retaining bar 3 are cut off at an angle, as indicated at 3^a, and the base of the bifurcation in the end of the stem 6 is formed with a correspondingly inclined shoulder, as 100

105 shown by dotted lines on Figure 2, so that when the retaining bar is swung outwardly in alignment with the stem the beveled end 3^a thereof will abut against the shoulder at the inner end of the bifurcation and limit 110 the swinging movement of the bar. The bar is thus held in alignment with the stem so

that the card 2 or like member can readily be placed in position on the stem or removed therefrom, the bar being of such a width as to pass freely through the opening in a longitudinal direction. After the card has been placed in position the bar 3 is swung into a position at right angles to the stem 9 and then moved over the pin 8 to bring the pin to the inner end of the slot 9. The arrangement of the device is preferably such that the retaining bar will drop into such a position by gravity, the slotted portion of the bar being at the lower end thereof. The slot 9 is also preferably inclined with respect to the longitudinal axis of the retaining bar 3, so that as the retaining bar is moved longitudinally to bring the pin 8 toward the inner end of the slot 9, the pin and slot will have a cam action to force the bar toward the base 1 and clamp the card 2 in position.

A slight modification is shown by Figures 3 and 4, in which the base 1 is secured to the outer end of a supporting arm 10. The other end of the supporting arm may be secured to a suitable part of the building 11. As shown on the drawings, the base 1 is secured in position by means of a centrally located screw 5, and in the modification shown by Figures 3 and 4 this screw is caused to engage a knob or enlargement 10^a at the outer end of the arm 11 instead of being threaded in the side of a house or the like, as shown by Figure 2. The card or sign 2 may be of any suitable type and may have any desired announcement printed or marked thereon. The sign is formed with a suitable opening to receive the stem 6, and the retaining bar can be quickly moved into position, as previously described, either to clamp the card in position or permit it to be applied to the stem or removed therefrom.

Any suitable means may be provided for engaging the supporting arm 10 to hold it in position. As shown by Figures 3 and 4, a keeper 12 is secured to the side of the building and the end of the arm 10 can be slidably inserted in the keeper when it is desired to secure the arm in position. The arm can be moved in and out within the keeper and a set screw 13 is provided for clamping the arm in position when it has been properly adjusted. The keeper may be permanently secured to the desired portion of the building and admits of the arm being placed in position or removed therefrom at any time when such may be desired.

Having thus described my invention what I claim as new and desire to secure by Letters Patent is:

1. The combination with a perforated

card, of a base, a stem projecting from the base and adapted to be received in the perforation of the card, and a retaining bar 65 having a pin and longitudinally extending slot connection with the stem whereby it can be swung into alignment with the stem when placing the card in position or removing it therefrom and swung into a position transverse to the stem to engage and hold the card in contact with said base.

2. The combination with a perforated card, of a base, a stem projecting from the base and adapted to be received in the perforation of the card, a pin on the stem, a retaining bar having a slot therein which slidably receives the pin and extends toward an end of the bar so that the bar can be swung into alignment with the stem when the pin is at one end of the slot and will hold the card in place on the stem when the pin is at the other end of the slot.

3. The combination with a perforated card, of a base, a stem projecting from the base and adapted to be received in the perforation of the card, a retaining bar having a pin and slot connection with the stem for relative travel whereby it can either be swung into alignment with the stem to admit of the card being placed in position or removed therefrom or swung into a position at right angles to the stem to hold the card in place, the slotted portion of the connection having a cam formation to force said bar toward the card being clamped against the base.

4. The combination with a perforated card, of a base, a stem projecting from the base and adapted to be received in the perforation of the card, a pin on the stem, a retaining bar having a slot therein which is inclined with respect to the axis of the bar and extends toward one end thereof, said slot slidably receiving the pin on the stem 100 so that the retaining bar can be swung into alignment with the stem when the pin is moved to one end of the slot, and the bar being slidably longitudinally when in a position at right angles to the stem to clamp the card against the base by the cam action between the pin and inclined slot.

5. The combination with a card, of a base against which the card is adapted to fit, a positioning stem projecting from the base 115 and adapted to engage the card to hold it in place, and a retaining bar having a pin and slot connection with the stem, the slot having a cam arrangement so that movements of the retaining bar will cause it to move laterally 120 of the pin to engage the card and clamp it against the base.

In testimony whereof I affix my signature,

WILLIAM S. BEAZELL.
